UNITED STATES PATENT OFFICE.

ANDREW LAING, OF NEWCASTLE-UPON-TYNE, ENGLAND.

BURNER FOR LIQUID FUEL.

1,160,910.

Specification of Letters Patent.

Patented Nov. 16, 1915.

Application filed August 11, 1913. Serial No. 784,258.

To all whom it may concern:

Be it known that I, ANDREW LAING, a subject of the King of Great Britain, residing in Newcastle-upon-Tyne, England, (whose post-office address is 15 Osborne road, Newcastle-upon-Tyne, in the county of Northumberland, England,) have invented certain new and useful Improvements in Burners for Liquid Fuel, of which the following is a specification.

This invention relates to liquid fuel burners for steam boiler and other furnaces, of the kind wherein the oil or other liquid fuel is sprayed or atomized by steam, the oil and steam being injected under pressure through two co-axial nozzles both delivering to an annular space encircling the steam nozzle, the construction and relation of the nozzles and the annular space being such that the oil is projected in an annular sheet into this space while the steam is directed across the space preferably in a forwardly and outwardly inclined direction so as to impinge upon the sheet of oil (already more or less broken up by its passage through the oil nozzle) while still more or less confined within the annular space, the impact of the converging sheets or streams of oil and steam completing the spraying or atomizing of the oil which is delivered to the furnace in a diffused ring of mist or spray.

This invention consists in improved construction and arrangements of parts according to which the inner or steam nozzle is in the form of a ring of separate nozzles. The aperture of the oil outlet or nozzle formed between the outer casing and the flared end of the steam supply tube is of annular character and is preferably adjustable in the known manner by the longitudinal displacement of the steam supply tube by means of a hand-wheel at the rear of the burner.

The improved construction is more specifically described with reference to the accompanying drawings, wherein—

Figure 1 is an elevation and Fig. 2 an end view of a burner embodying the present invention; Fig. 3 is a longitudinal section of the same; Fig. 4 is an elevation of part of the burner, and Fig. 5 an end view of the same; Fig. 6 is a longitudinal section through the nozzle; Fig. 7 is an elevation of the fuel valve and Fig. 8 an elevation of the fuel valve looking at these parts in opposite directions from chamber

E in Fig. 6. Figs. 4 to 8 being all on an enlarged scale as compared with Figs. 1 to 3.

The burner comprises a tubular body portion A within which is fitted a hollow spindle B so as to leave an annular fuel space C between the spindle and the body into which space the fuel is delivered through the fuel inlet branch C°. Steam is admitted through the steam inlet connection B° and the interior of the hollow spindle B and passages D in the body of a valve F secured upon the front end of the hollow spindle to a chamber E formed between the forward end of the body portion of the valve F and a cap H removably attached to the front end of the valve. This cap H also forms, in conjunction with the valve, the discharge orifices J through which the steam passes from the chamber E and by which it is directed more or less diagonally across an annular duct or space encircling the steam nozzle so as to impinge on the stream of oil issuing from the fuel nozzle into the said space and break up the same into exceedingly fine spray.

As shown more particularly in Figs. 6 and 7, the steam passes from the chamber E in an outward and forward direction through the series of small passages or orifices J which are annularly arranged and are preferably eccentrically disposed to impart a swirling or gyratory motion to the issuing jets of steam.

The mouth of the body portion A of the burner is suitably beveled to form a seat G for the valve F, the extent of the opening between which and the coöperating face of the valve can be adjusted as desired, for example, as shown in Figs. 1, 2 and 3, the valve and cap may be movable relatively to the body portion A by means of a hand wheel K which is screwed upon the rear end of the tubular spindle B and is so coupled with the body portion as to slide the tubular spindle B with valve and cap longitudinally relatively to the body portion A and thereby vary the extent of the fuel opening.

Having thus described the nature of my said invention and the best means I know of carrying the same into practical effect, I claim:

1. In a liquid burner, the combination of an outer tubular inclosing member or casting provided with an oil supply inlet port and having a cylindrically bored rear part and a conically bored front part, a co-axi-

- ally arranged inner tubular member having an outwardly flaring front part projecting into the said conically bored part and forming therewith an annular passage, a steam 5 inlet connection attached to the inner tubular member, the latter member forming with the said cylindrically bored part an oil channel having an outlet adapted to discharge oil into the said annular passage, and 10 a cap removably attached to the front end of the inner tubular member and forming therewith a nozzle comprising a series of 15 annularly disposed jet orifices adapted to discharge steam into said passage in advance of said outlet, substantially as described. 2. In a liquid burner, the combination of an outer tubular inclosing member or casing provided with an oil supply inlet port and having a cylindrically bored rear part and a 20 conically bored front part, a co-axially arranged inner tubular member having an outwardly flaring front part projecting into the said conically bored part and forming therewith an annular passage, a steam inlet 25 connection attached to the inner tubular member, the latter member forming with the said cylindrically bored part an oil channel having an outlet adapted to discharge oil into the said annular passage, a 30 cap removably attached to the front end of the inner tubular member and forming therewith a nozzle, and means for adjusting the discharge from said outlet independently of the discharge from the steam nozzle, said nozzle comprising a series of 35 annularly disposed jet orifices and adapted to discharge steam into said passage in advance of said outlet, substantially as described. 40 3. In a liquid burner, the combination of an outer tubular inclosing member or casing provided with an oil supply inlet port and having a cylindrically bored rear part and a 45 conically bored front part, a co-axially arranged inner tubular member having an outwardly flaring front part projecting into the said conically bored part and forming therewith an annular passage, a steam inlet 50 connection attached to the inner tubular member, the latter member forming with the said cylindrically bored part an oil channel having an outlet adapted to discharge oil into the said annular passage, a cap removably attached to the front end of the inner tubular member and forming therewith a nozzle, said nozzle comprising a series of annularly disposed jet orifices and adapted to discharge steam into said passage in advance of said outlet, substantially as described. 55 the said cylindrically bored part an oil channel having an outlet adapted to discharge oil into the said annular passage, a cap removably attached to the front end of the inner tubular member and forming therewith a nozzle, said nozzle comprising a series of annularly disposed jet orifices and to discharge steam into said passage in advance of said outlet, and means for moving the inner tubular member and the cap 60 together relatively to the said co-axially bored front part, thereby adjusting the discharge from the oil channel outlet independently of the steam nozzle discharge, substantially as described. 65 4. In a liquid fuel burner, the combination of a hollow body portion having a fuel admission port and comprising a rear part cylindrically bored communicating with the port and a conically bored forward mouth 70 part with an outwardly flaring wall, a longitudinally adjustable tubular spindle located within the said cylindrically bored part and communicating with a steam inlet port, a hollow valve member mounted on 75 the forward end of the tubular spindle having an outwardly flaring front end projecting into the conically bored part and forming therewith an annular passage surrounding said flared front end, said valve forming with the forward end of the cylindrically bored part an annular fuel nozzle adapted to discharge into the rear portion of the said annular passage, a cap mounted on the front end of the valve member and having a plurality of outwardly directed peripherally disposed passages forming with said end a series of steam jet outlets adapted to discharge into and across the annular passage in advance of the said fuel 80 nozzle, and means for moving the valve and cap together relatively to the said body portion, substantially as described. 85 In testimony whereof I have signed my name to this specification in the presence of 90 two subscribing witnesses. 95
ANDREW LAING.
